US00D959630S

(12) **United States Design Patent** (10) **Patent No.:** **US D959,630 S**
Choi et al. (45) **Date of Patent:** **** Aug. 2, 2022**

(54) **AIR PURIFIER**

(71) Applicant: **Samsung Electronics Co., Ltd.**, Suwon-si (KR)

(72) Inventors: **Minkyung Choi**, Suwon-si (KR); **Cheolyeon Jo**, Suwon-si (KR); **Kangdoo Kim**, Suwon-si (KR)

(73) Assignee: **Samsung Electronics Co., Ltd.**, Suwon-si (KR)

(**) Term: **15 Years**

(21) Appl. No.: **29/750,955**

(22) Filed: **Sep. 17, 2020**

(30) **Foreign Application Priority Data**

(57) **CLAIM**

We claim the ornamental design for an air purifier, as shown and described.

DESCRIPTION

FIG. 1 is a front perspective view of an air purifier showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is another front perspective view thereof;

FIG. 9 is an enlarged view of the encircled portion in FIG. 1; and,

FIG. 10 is a front perspective view of the air purifier shown in a state of use with the lid portion in a raised position. The broken lines in the figures depict portions of the air purifier which form no part of the claimed design.

The dot-dash broken lines encircling portions of the claimed design that are illustrated in enlargements form no part of the claimed design.

1 Claim, 10 Drawing Sheets
